CONTAINER CLOSURE

Ray L. Smith, Cheyenne, Wyo.

Application June 13, 1938, Serial No. 213,345

5 Claims. (Cl. 221—60)

This invention relates to containers adapted for the intermittent dispensing of commodities in powder, paste, cream, or similar form, and more particularly to containers of collapsible type adapted to yield to external pressures for the extrusion of their contents, and has as an object to provide an improved closure for such containers.

A further object of the invention is to provide an improved container closure assembly arranged to prevent separation of the closure element from the container.

A further object of the invention is to provide an improved container closure assembly including a closure element conveniently movable between opening and closing relation with the container without actual separation of said element from its associated container.

A further object of the invention is to provide an improved construction and cooperative arrangement of elements constituting a non-separable closure for containers.

A further object of the invention is to provide an improved construction and combination of elements constituting a non-separable closure assembly readily adaptable for operative association with containers of varying specific forms, types, and constructions.

A further object of the invention is to provide an improved non-separable closure assembly for containers which is simple, convenient, and inexpensive of manufacture; which is susceptible of ready adaptation to and in operative association with conventional containers; which is positive and efficient in use; and which is entirely free from any detachable element susceptible of loss through separation from the assembly.

My invention consists in the construction, arrangement, and combination of elements herein-after set forth, pointed out in my claims, and illustrated by the accompanying drawing, in which—

Figure 1 is a fragmentary, detail section through the dispensing end of a conventional container wherewith a preferred embodiment of the invention is operatively associated as in closing relation with the container. Figure 2 is a view similar to Figure 1 showing the elements of the latter figure positioned to permit discharge from the container. Figure 3 is a fragmentary, detail section through an alternative association of the invention with the dispensing end of a container. Figure 4 is a view similar to Figure 3 and illustrating a further modified embodiment of the invention. Figure

5 is a view similar to Figure 4 illustrating still further structural modifications of the invention as adapted for association with containers of certain types.

Dispensing containers of various specific types, 5 including collapsible tubes, have come into general and widespread use for the packaging and dispensing of a wide range of varying commodities, the vast majority of conventional dispensing containers having one common fault in 10 that the dispensing orifice is normally closed by a separable cap which is susceptible of escape from the user with consequent danger of loss, and the instant invention is concerned with the provision of improved closure means for dispensing containers so constructed and arranged 15 as to preserve all of the advantages of conventional containers and at the same time completely preclude the possibility of separation of the closure element from its associated container. 20

In the embodiment of the invention shown in Figures 1 and 2, the improvement is illustrated as operatively associated with the dispensing end of a conventional container or tube 10 which is formed with a central, axially-extending neck 11 formed with a laterally-directed discharge opening 13 adjacent the junction of the neck 11 and tube 10. To selectively open and close the discharge orifice 13, a cylindrical plunger 12 is 25 fitted closely within the cylindrical bore of the neck 11 for rotation and axial reciprocation relative to said neck, and the plunger 12 is formed on or secured to the inner end of a threaded stem 14 which has a maximum diameter no greater 30 than that of the plunger 12 and a length sufficient to extend to or beyond the outer end of the neck 11 when the plunger 12 is positioned with its side wall completely obstructing the orifice 13. The bore of the neck 11 is smooth, 35 straight, and unobstructed for a distance outwardly of said neck sufficient to accommodate the plunger 12 in clearing relation with the orifice 13 as is clearly shown in Figure 2, and the outer extremity of said neck 11 is formed with 40 internal threads adapted to engage and cooperate with the threads of the stem 14, the threads on the neck 11 having a minimum diameter less than that of the plunger 12 so that the latter may not pass through the threaded portion 45 of the neck wherewith it is mounted. A suitable thumb-nut or manipulating head 15 is fixed to the outer end of the stem 14 in position to overlie and engage at times against the outer end of the neck 11 and thereby limit travel of 50 55

- the plunger 12 and stem 14 inwardly of said neck to a position corresponding to that shown in Figure 1, wherein the plunger 12 is disposed to close off and obstruct the orifice 13, the inward 5 extension of the internal threads in the neck 11 being limited to a distance which will permit the plunger 12 to move outwardly of the neck sufficiently to entirely clear and consequently open the orifice 13, it being obvious that rotation of 10 the stem 14 and plunger 12 transmitted through the head 15 in one direction will operate to move the plunger 12 outwardly of the neck to the limit permitted by the threaded portion of said neck and to the position shown in Figure 2, 15 thus uncovering the orifice 13 to permit dispensing of contents from the container 10 through said orifice, while reverse rotation of the plunger, stem, and head unit will act to move said plunger inwardly of the neck 11 and into closing relation 20 with the orifice 13. When the improvement just described is to be developed in connection with containers having neck portions of relatively ductile material, the neck portion 11 may have a uniform, straight bore sufficient to accommodate 25 the plunger 12 within which the unit 12, 14, 15 is positioned with the plunger 12 in clearing relation with the orifice 13, whereafter the material adjacent the extremity of the neck may be rolled or circumferentially pressed into intimate 30 engagement with the threaded stem 14 to form the desired internal threads on the neck portion. In other specific constructions, the head 15 may be initially separate from the stem 14 to permit insertion and threaded engagement 35 of the stem and plunger unit through the open bottom of the container 10 and into the desired relation with the neck 11, whereafter the head 15 may be suitably fixed to the outer end of the stem 14.
40. In the modification according to Figure 3, the essential elements of the invention are in all respects identical with the disclosure hereabove described, the only difference being that the discharge orifice 13 is directed axially of the container 10 for end discharge, in which case the neck 11 is disposed to project laterally across the container end to cooperate with a laterally-disposed unit 12, 14, 15 in the manner hereabove set forth, it being apparent that the container 45 may communicate directly with a single orifice 13 in the manner first described, or with an elongated discharge passage determining in the orifice 13 and disposed for interruption by the plunger 12.
50. The modification illustrated in Figure 4 is functionally identical with the showing of Figure 3 and differs from the latter only in that the container 10 is "streamlined" or contoured to house the closure assembly smoothly within its discharge end.
55. The construction shown in Figure 5 is adapted for enclosure within a smoothly-contoured container and differs from that shown in the preceding figures in that the plunger 12 is mounted to slide laterally of the container end into and out of closing relation with the orifice 13 within a cylindrical chamber 16 which intersects the discharge passage from the container and which communicates at one end with a threaded bore extension 17, and in that said plunger 12 is fixed 60 to an operating stem 18 which extends in one direction therefrom to rigid connection with an enlarged, externally-threaded stem portion 14 seated in and cooperating with the threaded bore extension 17, and in the opposite direction 65
- 70
- 75

through a suitable bore in the container end to fixed connection with the manipulating head 15, so that discharge from the container may be had when the plunger 12 has been moved out of obstructing relation with the orifice 13, between said plunger 12 and threaded stem 14 and about that portion of the stem 18 interconnecting said elements. 5

Since it is readily apparent that the alternative embodiments of the invention illustrated 10 and described do not exhaust the possible practical adaptations of the invention to specific types and constructions of containers, and since variations, changes, and modifications in the specific form, construction, and arrangement of 15 the elements shown and described may be had without departing from the spirit of my invention, I wish to be understood as being limited solely by the scope of the appended claims, rather than by any details of the illustrative 20 showing and foregoing description.

I claim as my invention—

1. A non-separable closure for containers comprising, a hollow neck on said container, a discharge orifice opening laterally through a wall 25 of said neck, a plunger element movable longitudinally of said neck into and out of closing relation with said orifice, contracted means in the outer neck portion engageable at times by said plunger to limit travel thereof outwardly 30 of said neck, and manually-operable means for shifting said plunger.

2. A non-separable closure for containers comprising, a hollow neck associated with said container, a discharge orifice opening through one 35 wall of said neck, a plunger slidable in said neck into and out of closing relation with said orifice, a threaded stem of reduced diameter, fixed to said plunger longitudinally and outwardly of said neck, internal threads adjacent the outer 40 extremity of said neck cooperating with said threaded stem and engageable at their inner ends by said plunger at times to limit travel of said plunger outwardly of said neck, and means manually-engageable to rotate said stem. 45

3. A non-separable closure for containers comprising, a hollow neck associated with said container, a discharge orifice opening through one wall of said neck, a plunger slidable in said neck into and out of closing relation with said orifice, means engageable with the outer end of said neck and secured to said plunger to limit travel of the latter inwardly of said neck to a position obstructing said orifice, means intermediate said plunger and the end of said neck engageable by 55 the former at times to limit travel of said plunger outwardly of said neck to a position in clearing relation with said orifice, and means manually-engageable without said neck for the selective positioning of said plunger. 60

4. A non-separable closure for containers comprising, a discharge passage for the container, a hollow cylindrical member intersecting said passage, a cylindrical plunger fitted within and to slide along said member into and out of obstructing relation with said passage, means for limiting travel of said plunger in one direction to a position obstructing said discharge passage, means limiting travel of said plunger in the opposite direction to a position in clearing relation 65 with said discharge passage, and manually-engageable means for the selective positioning of said plunger. 70

5. A non-separable closure for containers comprising, a discharge passage for the container, a 75

bore intersecting said passage, a plunger fitted within and to slide along said bore into and out of obstructing relation with said passage, a stem fixed to said plunger and extending to connection of its outer end with a manipulating head exteriorly of said neck, threads on said stem of no greater maximum diameter than the plunger,

and cooperating internal threads in the outer portion of said bore to prevent escape of said plunger outwardly therefrom and to provide means for feeding said plunger into and out of obstructing relation with said discharge passage. 5
